UNITED STATES PATENT OFFICE.

FRANK DUTCHER, OF VERSAILLES, PENNSYLVANIA, ASSIGNOR TO CENTRAL RAILWAY SIGNAL COMPANY, OF PITTSBURGH, PENNSYLVANIA, A CORPORATION OF NEW JERSEY.

RAILWAY SIGNAL-TORPEDO.

1,205,869.

Specification of Letters Patent.

Patented Nov. 21, 1916.

Application filed April 22, 1915. Serial No. 23,176.

To all whom it may concern:

Be it known that I, FRANK DUTCHER, a citizen of the United States, residing at Versailles, in the county of Allegheny and State of Pennsylvania, have invented certain new and useful Improvements in Railway Signal-Torpedoes, of which the following is a specification, reference being had therein to the accompanying drawing.

10 This invention relates to improvements in railway signal torpedoes, and pertains to that general type which is known as fiber or non-flying torpedoes.

15 The species of this type of torpedo to which the present invention pertains is that in which the case is made from a paper tube.

20 My present improvement pertains to extending the ends of the tube sufficiently beyond the explosive to enable them to be doubled under the body of the torpedo and fastened together by a suitable metal clip.

25 The present invention further relates to having the doubled under ends of the tube lap each other and these lapping ends secured by a metal clip, the metal clip and the lapping ends also serve to hold the lead rail-engaging strap to the torpedo.

30 Referring now to the drawings Figure 1 is a perspective view of my improved torpedo showing it in position upon a rail. Fig. 2 is a longitudinal sectional view on the line 2—2 of Fig. 1. Fig. 3 is a central sectional view at right angles to Fig. 2. Fig. 35 4 is a view showing the paper tube with the ends extended outward and before they are doubled back under the explosive and also the metal clip before it is applied. Fig. 5 is a view showing the ends of the tube extended and a tablet explosive in dotted lines therein.

35 My improved torpedo is made from a paper tube 1, which will have inserted therein midway between its ends a tablet charge explosive. In Fig. 4 the explosive charge 2 is in the form of a tablet, while in Fig. 5 the explosive 3 is in a powdered form. After the explosive is placed midway in the tube, as shown either in Figs. 4 or 5, the extended 45 flattened ends 4 of the tube are doubled back under the main or body-portion, as shown in Fig. 1. A metal clip 5 is passed between the inner turned back end 4 and the body of

the torpedo, and this clip is provided with projections or lugs 6, which are doubled down and under the outer turned end 4, thus uniting these turned back ends of the tube and also holding in place a suitable rail-engaging strap 7, which as here shown passes between the two lapping ends 4 of the tube. It will be understood, of course, the tube when made is round and it is then afterward suitably shaped or flattened, as shown in Figs. 4 and 5, after which the explosive charge, either in powdered form or in tablet form, is placed therein. In torpedoes of this construction the metal clip is completely under the torpedo so that no part of it will fly to injure by-standers when the torpedo explodes. Furthermore, it will be a torpedo that will be easily made waterproof, because after the tube is paraffined and doubled back under the body-portion, as shown, there is no opportunity for water to reach the explosive. A compact and efficient torpedo is the result of the construction herein shown and described.

Having thus described my invention, what I claim and desire to secure by Letters Patent is:

1. An improved torpedo comprising a tubular fiber casing, an explosive placed therein, the ends of the tube extended beyond the explosive and doubled under the body-portion, a clip extending under the body of the torpedo and transverse thereof, the ends of the clip bent around and clamping the bent under ends of the tube thus closing their ends and holding them in position.

2. An improved torpedo comprising a fiber tube, an explosive therein, the ends of the tube extended beyond the explosive and doubled inward under the body of the torpedo, a clip extending under the body portion and transverse thereof, the ends of the clip clamping the turned under ends of the tube, and a rail-engaging strap held to the torpedo by one of the said turned under ends and the clip.

In testimony whereof I hereunto affix my signature in the presence of two witnesses.

FRANK DUTCHER.
